UNITED STATES PATENT OFFICE

152,821

DESIGN FOR A RINGTOSS GAME TARGET

James R. O'Neil, San Francisco, Calif.

Application April 14, 1947, Serial No. 138,387

Term of patent 14 years

(Cl. D34—5)

To all whom it may concern:

Be it known that I, James R. O'Neil, a citizen of the United States, and a resident of the city and county of San Francisco, State of California, have invented a new, original, and ornamental Design for a Ringtoss Game Target, of which the following is a specification, reference being had to the accompanying drawing, forming part thereof:

Figure 1 is a perspective view of the ringtoss game target showing my new design.

Figure 2 is a top plan view of the ringtoss game target.

Figure 3 is a front elevation of the ringtoss game target.

Figure 4 is a side elevation of the ringtoss game target.

I claim:
The ornamental design for a ringtoss game target, as shown.

JAMES R. O'NEIL.
